UNITED STATES PATENT OFFICE.

FRANK X. LIST, OF NEW YORK, N. Y., ASSIGNOR TO NATIONAL CARD MOUNTING COMPANY, OF NEW YORK, N. Y., A CORPORATION OF NEW YORK.

DISPLAY STAND.

Application filed June 7, 1923. Serial No. 643,953.

To all whom it may concern:

Be it known that I, FRANK X. List, a citizen of the United States, and a resident of New York, borough of Bronx, in the county of Bronx and State of New York, have invented certain new and useful Improvements in a Display Stand, of which the following is a full, clear, and exact specification.

10 This invention relates more particularly to a class of knock-down or foldable easel devices.

My invention has for its object primarily to provide a device or stand designed to be employed for displaying in stores and elsewhere merchandise and various articles as well as advertisements in a manner whereby the attention of persons will be attracted thereto, and which is of a form adapted 20 to be made of foldable cardboard or other suitable material of component parts so that by the process of folding and unfolding the device may be packed and shipped in flat condition to avoid bulky packages when 25 transported or when kept in stock, besides permitting of being easily folded into usable form when desired.

The invention resides mainly in the provision of a front member adapted to be disposed in upstanding position, and this member is cut and folded from a single blank providing spaced superposed ledge members or steps or platforms relatively arranged in the fashion of a stairway to allow articles to be removably arranged for display on tops of the ledge members or steps or to permit advertising matter to be displayed on the tops of steps as well as on the risers thereof. The front member 30 is supported in upright position by an easel member which is secured on the rear face of the front member, and the easel members preferably composed of a lower section and an upper section. The lower 40 section is cut and folded from a single blank providing movable wing members adapted to be swung toward and from extending spaced upright positions relative to the front member, and each wing member 45 has a notch provided between a pair of tab members in opposed relation to the upper section of the easel. The upper section is also preferably cut and folded from a single blank providing spaced locking tongues arranged for being removably inserted in the

notches of the pairs of tab members of the wing members of the lower section when swung from the front member, in order to releasably lock the sections of the easel member together for holding the front member 60 in upstanding position.

A further object of the invention is to provide a display stand of a simple, efficient and durable construction which may be made in either plain or fanciful shapes in 65 any appropriate size.

With these and other objects in view, the invention will be hereinafter more fully described with reference to the accompanying drawings forming a part of this specification in which similar characters of reference 70 indicate corresponding parts in all the views, and will then be pointed out in the claims at the end of the description.

In the drawings, Figure 1 is a perspective view showing a front elevation of one form of display stand embodying my invention.

Fig. 2 is an enlarged perspective view showing a rear elevation of the device.

Fig. 3 is an enlarged plan of the blank from which the front member is made.

Fig. 4 is an enlarged plan of the blank from which the lower section of the easel member of the device is made, and

Fig. 5 is an enlarged plan of the blank from which the upper section of the easel member is made.

The device or display stand has a front member 10 supported by an easel member 11 90 which is preferably divided into a lower section 12 and an upper section 13, and these parts of the stand may be made in various sizes and shapes as occasion requires.

The front member 10 is preferably cut 95 from a sheet of foldable cardboard or other suitable material to provide a blank 14, Fig. 3, having substantially rectangular sections or panels, as 15, 16, 17, which are longitudinally disposed in superimposed relation. 100 The panel 16 may be shorter than the panel 15 and the panel 17 may be shorter than the panel 16 so that the panels are in relative pyramidal arrangement, and the upper corners of each panel of the blank may be cut 105 on an incline or on a bevel, as at 18, 18'. The blank may also be formed with a surface or peak member section, as 19, of a partial circular shape of a size so that it surrounds the uppermost panel 17, and this 110

surface member is provided by slitting spaced parts of the blank, as at 20, 20^a, which slits provide the upper portion of the panel 17. At the junctures of the panels 15, 5 16, 17 and at the juncture of the panel 17 with the surface member 19 spaced parts of the blank are scored, as at 21, 21^a, 22, 22^a, 23, 23^a. By folding parts of the blank angularly toward its rear face on the scorings 21, 22, 23 and then folding parts of the blank angularly upward on the scorings 21^a, 22^a, 23^a the front member 10 will be formed to provide superposed ledge members or steps or platforms, as 24, 25, 26, relatively disposed in stairway arrangement with the ledge members being of variable widths. Each ledge member or step is thereby formed with a riser 27 and a top surface 28. The surface member 19 will then be 10 spaced rearwardly of the ledge member 26 as well as being disposed in surrounding relation to the upper part of this ledge member, as shown in Figs. 1 and 2. When the front member 10 is disposed in upstanding position with the lower edge of the ledge member resting on a suitable support, the top surfaces 25 of the ledge members will be flatwise on longitudinal planes for permitting merchandise and other articles to be 15 displayed thereon, or the top surfaces 28 of the ledge members may be disposed on inclines so that advertisements may be inscribed on their front faces as well as on the front faces of the risers 27 and on the front 20 face of the surface member 19.

The lower section 12 of the easel member 11 is preferably cut from a sheet of foldable cardboard or other appropriate material to provide a blank 29, Fig. 4, having a 19 rectangled lower portion 30 and convergently inclined side edges, as 31, 32, above the side edges of the rectangled portion. The blank 29 is slitted crosswise, at 33, 34, from approximately the central parts of the 25 side edges of the rectangled lower portion 30 toward the central part of the blank. These slits are on alignment as well as terminating in spaced relation. The spaced parts of the blank 29 at the inner ends of 30 the slits 33, 34 are scored vertically, as at 35, 36, and this blank is also scored crosswise, as at 37, between the spaced inner ends of the slits 33, 34. The portion of the blank 35 between the scorings 35, 36, 37 provide a panel 38, and the parts of the blank embraced within the scorings 35, 36, slits 33, 34 and the inclined edges 31, 32 provide wing members or supports 39, 40 having in the edges of their upper ends notches 41, 42 40 formed between pairs of tab members 43, 43^a and 44, 44^a, respectively. The portion of the blank 29 below the slits 33, 35 and the scoring 37 provides a substantially rectangular bracket member 45, and the part 45 of the blank centrally of this bracket mem-

ber is scored crosswise, as at 46, to allow the bracket to be angularly flexed transversely under the wing members 39, 40. The upper end of the panel 38 of the blank 39 is glued or otherwise fastened to the rear face of the 70 riser 27 of the ledge member 25, and the part of the bracket member 45 below the scoring 46 is cemented or otherwise fastened to the rear face of the riser 27 of the ledge member 24. When the front member 10 is foldably formed for providing the ledge members 24, 25, 26, as below explained, the blank 29 is bent on the scorings 35, 36 so that the wing members 39, 40 may be swung 75 toward each other to positions extending rearwardly of the front member, and the bracket member 45 is bent on the scoring 46 to foldably hold the wing members in spaced relation to the ledge member 24 of the front member. The pairs of tab members will 80 then be in spaced proximity to the lower part of the ledge member 26 of the front member. The pairs of tab members will 85

The upper section 13 of the easel member 11 is cut from a sheet of foldable cardboard or other suitable material to provide a blank 47, Fig. 5, having a substantially rectangular body portion, as 47^a, with a reduced upper end, as 48. The blank has in spaced relation to its lower end a transverse 90 scoring 49, and the body portion 47^a terminates at this scoring. The part of the blank 47 below the scoring 49 provides an extensibly adjustable bracket member 50 having in its central part a crosswise scoring 51 95 in spaced parallel relation to the scoring 49. In the central part of the bracket member 50 and between the scorings 49 and 51 are two spaced angular slits, as 52, 53, to provide two oppositely protruding locking tongues 100 54, 55 which are spaced from each other for being removably admitted in the notches 41, 42 between the pairs of tab members 43, 43^a and 44, 44^a of the wing members 39, 40 of the lower section of the easel when the 105 wing members are normally positioned in protruding relation rearwardly of the front member. The reduced upper end 48 of the body portion 47^a of the blank 47 is glued or otherwise fastened to the central part of the surface member 19 of the front member, and the lower part of the bracket member 50 is cemented or otherwise fastened to the rear face of the riser 27 of the ledge member 26 of the front members so that the locking 110 tongues 54, 55 overhang the upper part of the panel 38 of the lower section of the easel. When the stand is foldably arranged for use with the wing members 39, 40 of the lower section of the easel being swung to extending positions rearwardly of the front member, as above described, the bracket member 50 of the blank 47 is bent angularly on the scorings 49, 51 to space the body portion 47^a of this blank from the riser 27 of

the ledge member 26 of the front member. By then inserting the tongues 54, 55 in the notches 41, 42 of the wing members 39, 40 the sections of the easel will be releasably locked for supporting the front member against liability of accidental collapsing. By reversely moving the various parts of the display stand it will be folded to allow of being packed and transported in flat form.

10 In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

20 Having thus described my invention, I claim as new and desire to secure by Letters Patent:—

1. In a display stand, the combination with an upstanding front member cut and folded from a single blank to form spaced superposed ledge members disposed in substantially stairway arrangement, of an easel member supporting the front member, said easel member composed of separate lower and upper sections, the lower section cut and folded from a single blank to form at its side parts spaced movable substantially triangular wing members and an extensibly foldable bracket member at the lower ends of the wing members, the upper parts of the blank between the wing members secured to the rear face of one of the upper ledge members of the front member whereby the wing members may be swung in lateral directions toward and from each other rearwardly of the central parts of the ledge members and the bracket member having a portion secured to the rear face of the lowermost ledge member for foldably positioning the wing members in spaced relation to the lower ledge member, each of said wing members also having in its upper end a notch forming a pair of tab members, said separate upper section of the easel member cut and folded from a single blank to form a body portion with spaced locking tongues, the upper edge of said body portion secured to the rear face of the front member whereby the locking tongues may be removably inserted in the notches of the pairs of tab members of the lower section when the wing members are swung toward each other.

2. In a display stand, the combination with an upstanding front member cut and folded from a single blank to form spaced superposed ledge members of different widths disposed in substantially stairway arrangement as well as forming a surface member extending upwardly and rearwardly from the uppermost ledge members, of an easel

member supporting the front member, said easel member composed of separate lower and upper sections, the lower section cut and folded from a single blank to form at its side parts spaced movable substantially triangular wing members, the upper part of the blank between the wing members secured to the rear face of one of the upper ledge members of the front member whereby the wing members may be swung in lateral directions toward and from each other rearwardly of the central parts of the ledge members, each of said wing members also having in its upper end a notch providing a pair of tab members, said upper section of the easel member cut and folded from a single blank to form a body portion with spaced locking tongues depending from its lower edge, the upper edge of said body portion secured to the rear face of the surface member of the front member whereby the locking tongues may be removably inserted in the notches of the pairs of tab members of the lower section when the wing members are swung toward each other.

3. In a display stand, the combination with an upstanding front member cut and folded from a single blank to form spaced superposed ledge members of different widths disposed in substantially stairway arrangement as well as forming a surface member extending upwardly and rearwardly from the uppermost ledge member, of an easel member supporting the front member, said easel member composed of separate lower and upper sections, the lower section cut and folded from a single blank to form at its side parts spaced movable wing members and an extensibly foldable bracket member at the lower ends of the wing members, the upper part of the blank between the wing members secured to the rear face of one of the intermediate ledge members of the front member whereby the wing members may be swung in lateral directions toward and from each other rearwardly of the central parts of the ledge members and the bracket member having a portion secured to the rear face of the lowermost ledge member for foldably positioning the wing members in spaced relation to the lower ledge member, each of said wing members also having in its upper end a notch providing a pair of tab members, said upper section of the easel member cut and folded from a single blank to form spaced locking tongues for removable insertion in the notches of the pairs of tab members of the lower section when the wing members are swung toward each other.

4. In a display stand, the combination with an upstanding front member cut and folded from a single blank to form spaced superposed ledge members of different widths disposed in substantially stairway

arrangement as well as a surface member extending upwardly and rearwardly from the uppermost ledge member, of an easel member supporting the front member, said easel member composed of separate lower and upper sections, the lower section cut and folded from a single blank to form at its side parts spaced movable wing members and an extensibly foldable bracket member 5 at its lower ends, the upper part of the blank between the wing members secured to the rear face of one of the intermediate ledge members of the front member whereby the wing members may be swung in lateral directions toward and from each other rearwardly of the center of the ledge members and the bracket member having a portion secured to the rear face of the lowermost ledge member for foldably positioning the 10 wing members in spaced relation to the lower ledge member, each of said wing members also having in its upper end a notch forming a pair of tab members, said upper section of the easel member cut and folded from a single blank to form a body portion 25 with spaced locking tongues depending from it, lower edge and also forming an extensibly foldable bracket on the lower edge of the body portion, the upper edge of said body portion secured to the rear face of the surface member of the front member and the bracket of the body portion being secured to the rear face of the uppermost ledge member whereby the locking tongues may be removably inserted in the notches of the 30 pairs of tab members of the lower section when the wing members are swung toward each other.

This specification signed this 6th day of June A. D. 1923.
